HELICOPTER

John E. Hess, Jr., New Westminster, British Columbia, Canada

Application October 15, 1935, Serial No. 45,907

3 Claims. (Cl. 244—6)

My invention relates to improvements in helicopters the objects of which are to provide means for stabilizing the machine when in flight; to provide automatic means for increasing the lift of one lifting propeller and to simultaneously reduce the lift of a complementary propeller, and to provide means serving as automatic stabilizers which also serve as planes for the helicopters in the event of the lifting power of the propellers being less than that necessary to keep the machine in flight.

The invention consists essentially of a pair of lifting propellers provided on the trailing edge of their blades with an aileron and means for moving the ailerons of one propeller up and those of the other propeller down, as will be more fully described in the following specification and shown in the accompanying drawings, in which:

Fig. 1 is a general rear elevational view of a helicopter showing the invention.

Fig. 2 is a plan view.

Fig. 3 is a fragmentary view of a propeller blade fitted with an aileron.

Fig. 4 is a sectional view through a blade and aileron showing the control cylinder.

Fig. 5 is a sectional view of the control system.

Fig. 6 is a sectional view of the oil feed gland to the aileron control cylinders.

Fig. 7 is a detail view of the automatic control switch.

Fig. 8 is a diagram showing the aileron control generally.

Fig. 9 is a detail view of the wing vane structure.

In the drawings like characters of reference indicate corresponding parts in each figure.

The numeral 1 indicates generally a fuselage or frame having a tail fin 2, a rudder 3 and a power plant not shown. Suitably driven from the power plant are horizontal shafts 4, each of which drives through a housing 5 and a vertical tubular shaft 6. These shafts are driven preferably in opposite directions and are each fitted with a lifting propeller 7 having radiating blades 8 of suitable pitch. The trailing edge of each blade 8 is fitted with an aileron 9 which may extend any desired distance along the blade from its outer periphery inwards. For the purposes of description the two propellers will be respectively referred to as 7A and 7B and their respective blades as 8A and 8B.

Housed within an opening in each propeller 55 blade 8 is a pair of hydraulic control cylinders which are respectively indicated by the numerals 10 and 11, each cylinder is fitted with a suitable piston 12, see details in Figure 4, and a connecting rod 13. The connecting rods engage opposing parts of a rocker arm 14, which is fulcrumed

in the body of the blade as at 15. From opposite ends of the rocker arm 14 wires 16 extend to opposite ends of an arm 17 which is secured to the aileron 9 at the point of its hinge pin 18. The cylinders 10 and 11 are each provided with a port 19 through which the fluid for operating the pistons is introduced and withdrawn.

Suitably mounted in the cockpit, not shown, are two operating cylinders 20 and 21 each of which are provided with spring returned pistons 22 and connecting rods 23. A T-shaped rocking lever 24 is mounted below the cylinders 20 and 21, the head member 25 of which is connected at opposite ends to the connecting rods 23, and the leg 26 is connected to two armatures 27 of two solenoids 28 and 29.

Two wires 30 are led from opposite ends of the head member 25 of the rocking lever 24 to the ends of a second rocking lever 31 (shown enlarged in Figure 5) which is connected to the base of the control stick 32, so that the operation of the T-shaped rocking lever 24 can be operated as desired by the pilot through the control stick should the solenoids be out of operation.

Each of the cylinders 20 and 21 is provided with a port 33 as an inlet and outlet for the operating fluid. A tube 34 leads from the port 33 of the cylinder 20 to the base of each of the shafts 6, and a tube 35 also leads from the port 33 of the cylinder 21 to the base of each of the shafts 6. These two tubes connect to a stationary part 36 of a gland 37 which is provided with a central passage 38 and an annular groove 39 on its upper face, the upper part 40, which is rotatable with the shaft, is provided with a complementary central passage 38 and an annular groove 39. The tube 34 connects with the central passage 38 of both parts of the gland and continues upwards to the upper extremity of the shaft 6 and there branches out to each of the control cylinders 11 of the blades 8A and the corresponding tube extends through the other shaft to the control cylinders 10 of the blades 8B; and in a corresponding manner the tube 35 connects with the annular groove 39 of the stationary part 36 and connects with the corresponding groove in the upper part 40, continuing upwards to the upper end of its shaft, thence branching out to the control cylinders. The tubes 35 passing to the blades 8A communicate with the control cylinders 10, and those passing to the blades 8B communicate with the control cylinders 11, by this means force exerted by the piston 22 of the operating cylinder 20 is transmitted through the control cylinders to depress the ailerons of the propeller blades 8A and to raise those of the propeller blades 8B.

A switch 41 is provided for controlling the pull of the solenoids, this switch consists of an insulated arm 42 which is pivotally mounted inter-

mediate its length upon a pin 43. Extending from each end of the arm is a laminated spring contact finger 44 and extending below the arm 42 is a pendulum 45 to maintain the arm in horizontal position. Suitably mounted on an insulated panel, not shown, are rheostats 46A and 46B, which are disposed adjacent the free ends of the contact fingers 44, each of the rheostats are provided with contact points 47 which are disposed along a curve X—X shown in dotted line, the innermost point is connected by a wire 48 to one of the solenoids 28 or 29 and banks of resistance are interposed between the innermost and outermost points 47, so that as the pendulum 45 swings the tip of the contact finger 44 which is approaching a rheostat will contact first the outermost point 47, interposing the maximum resistance in the line and then the next adjacent point, thus cutting out one bank of resistance and so on until the innermost point is reached. Obviously the points contacted will depend on the inclination of the machine, the resistance of the contact finger to bending and the resistance to flow of current will be reduced as the inclination of the machine increases.

From the diagram, Figure 8, it will be apparent that on the machine tipping downwardly on the left or with the propeller blades 8A lower than the blades 8B the pendulum 45 will swing to the left and current from the battery 49 will flow through the rheostat 46A and its contact finger, through the wire 50 to the solenoid 28, thence to ground, thus energizing the solenoid to draw in its armature and swing the rocking lever 24, thus urging the piston 22 upwards in the cylinder 20 and allowing the piston in the cylinder 21 to descend. The fluid expressed by the above movement from the cylinder 20 forces the pistons of half the control cylinders outwards as previously described, thus lowering the ailerons 8 of the propeller blades 8A and raising those of the blades 8B, so that the lifting force of 8A is increased and 8B is diminished, hence the machine will return to level flight and contact between the contact fingers 44 and the contact points 47 be broken.

Extending from the frame 1 are wing frames 51, see Figures 1, 2 and 9, which are set at a relatively acute dihedral angle to the transverse axis of the main frame. From the wing frames a plurality of vanes 52 are hingedly suspended, these vanes are hung with their longitudinal axes parallel to the longitudinal axis of the helicopter and are provided with suitable stops 53 to prevent them from swinging their free ends outwardly from the frame beyond a substantially vertical position, their transverse length is such that when closed or inclined to the angle of the wing frame, they overlap each other slightly and form in such position a wing capable of lending support to the machine in the same manner as the wing of a plane should the propellers fail to be rotating at lifting speed. The vanes are preferably connected together by a control wire 54 by which they may be manually drawn to closed position, as indicated in dotted line in Figure 9.

In the event of a side slip taking place, the air resistance will swing the vanes 52 of the wing frame which is leading downwards to close them one against the other, so that vertical support is provided on that side, whereas none is provided on the other side of the machine. By virtue of the dihedral angle thus present to the air, the

machine will return to horizontal flight and when the side slip is stopped gravity will cause the vanes to return to their normal substantially vertical position of suspension. Air is normally free to pass between the suspended vanes and therefore no resistance to vertical lift by the propellers is produced.

It will be apparent that the system of using a pair of lifting propellers fitted with ailerons on their blades may be used forward and to the rear of a ship to keep it on a level course or on any desired incline or decline.

While I have shown a hydraulic system employing pairs of control cylinders and a pair of operating cylinders, it will be obvious that single cylinders having double acting pistons may be used to effect the same purpose.

The invention as above described is drawn particularly to the automatic control of ailerons attached to the trailing edge of the blades of lifting propellers, but it is well within the scope of the present invention to control the ailerons of the wings, or the elevators of a conventional plane in the same manner by using a gravity operated device and hydraulic means to raise an aileron on one wing and correspondingly depress another on the opposite wing.

What I claim as my invention is:

1. A helicopter having a pair of transversely arranged lifting propellers, a supporting wing mounted transversely beyond the slip stream of each propeller, said supporting wings consisting of frames set to a dihedral angle and having a plurality of vanes hingedly mounted in said frames on axes wholly parallel to the line of flight and adapted normally to hang substantially in a vertical position whereby when the helicopter is in normal flight the slip stream of air from above passes freely through said vanes and whereby one end of each of said vanes is presented into the direct line of flight.

2. A helicopter having a pair of transversely arranged lifting propellers, a pair of frames extending transversely beyond said propellers, said frames pivotally supporting a plurality of vanes, said pivotal supports being wholly parallel to the line of flight of the helicopter, all of said vanes being outside the influence of the slip stream of the propellers and being adapted to hang vertically during normal flight and to freely pass air from above and to assume a substantially horizontal plane and form supporting wings when the propeller speed in flight is below lifting speed.

3. A helicopter having a pair of transversely arranged lifting propellers, a pair of frames extending transversely beyond said propellers, said frames pivotally supporting a plurality of vanes, said pivotal supports being wholly parallel to the line of flight of the helicopter, all of said vanes being outside the influence of the slip stream of the propellers and being adapted to hang vertically during normal flight and to freely pass air from above and to assume a substantially horizontal plane and form supporting wings when the propeller speed in flight is below lifting speed, said vanes being provided with means for restricting their pivotal movement whereby when side slip occurs in flight the vanes of the frame leading in the direction of the side slip will assume substantially normal position and the vanes in the opposite frame will remain vertical.

JOHN E. HESS, JR.
